UNITED STATES PATENT OFFICE.

GUSTAV H. KAEMMERLING, OF ERIE, PENNSYLVANIA, ASSIGNOR TO GENERAL ELECTRIC COMPANY, A CORPORATION OF NEW YORK.

ENGINE.

1,089,711.

Specification of Letters Patent. Patented Mar. 10, 1914.

Application filed April 19, 1913. Serial No. 762,198.

To all whom it may concern:

Be it known that I, GUSTAV H. KAEMMERLING, a citizen of the United States, residing at Erie, in the county of Erie and State of Pennsylvania, have invented certain new and useful Improvements in Engines, of which the following is a specification.

The present invention relates to engines, and more especially to internal combustion engines operating on the so-called high compression plan, wherein fuel is injected into a body of highly compressed air whose temperature is above the ignition temperature of the fuel.

15 The object of my invention is to improve the construction and operation of engines, and more especially of internal combustion engines of the character specified.

One of the improvements is attained by 20 so combining and arranging the moving parts that the stresses exerted by one part are balanced by another part without such stresses being transmitted to the crank-shaft bearings as is customary.

25 A second and very important improvement arising from the first is that the length of the engine for a given output is decreased. This decrease is due to the arrangement of the cranks on the main shaft 30 and of the connecting rods as will appear hereinafter.

For a consideration of what I believe to be novel and my invention, attention is directed to the accompanying description and 35 claims appended thereto.

In the accompanying drawings, Figure 1 is a view in side elevation of a three cylinder internal combustion engine; Fig. 2 is a transverse section of the same; Fig. 3 is a 40 plan view of the engine, and Fig. 4 is a detail view of a bridge member for reducing the side thrusts of the pistons on the outside cylinders.

5 indicates the base of the engine which 45 may be of any suitable construction. It is provided with bearings 6 for the main shaft 7, said shaft being provided with three cranks 8. Mounted on top of the base are three vertically disposed cylinders 9, 10 and 50 11. Each cylinder is provided with exhaust ports 12 and scavenging ports 13 controlled by the pistons. Fuel is admitted to the combustion space of the cylinder by one or more injectors 14, which may be of any suitable construction. By preference the injectors

are of the type in which compressed air is used for forcing the fuel into the combustion space against the compression pressure due to the action of the pistons. On the compression strokes of the pistons the 60 temperature of the air in the cylinders is increased to a value above the igniting temperature of the fuel. Thus it will be seen that the engine operates on the two-cycle high compression plan. Considered with 65 relation to the main shaft, each cylinder is provided with an inner piston 15 and outer piston 16. Connected to the inner pistons are cross-heads 17 and to the outer pistons are cross-heads 18, said cross-heads extending transversely of the engine. The inner piston of the central cylinder is connected to the outer pistons of the outside cylinders 70 9 and 11 by diagonally extending connecting rods 19 and 20 arranged in pairs both in front and in the rear of the cylinders. The outer piston of the central cylinder is connected by diagonally-extending rods 21 and 22 with the inner pistons of the outside cylinders 9 and 11, also arranged in pairs 75 both in front and in the rear of the cylinders. The upper ends of these rods are anchored in the cross-heads 18 and the lower ends in the cross-heads 17. The inner pistons of the three cylinders are connected to the cranks 8 by the connecting-rods 23, 24 and 25. The cross-heads are guided in 80 their vertical movements by guides 26 which either form continuations of the cylinder, or are secured to some part of the engine frame. 85

It will be noted that each of the center cross-heads is connected to two pairs of diagonally extending rods, one pair of rods being in front and the other in the rear of the cylinders, whereas each of the cross-heads of the outside cylinders is connected to two diagonal rods, one being in front and the other in the rear of the cylinders. This arrangement has the advantage of simplicity 95 of construction and a decreased number 100 of parts.

In such an engine it is necessary, if the best results are to be obtained, to supply air for scavenging purposes under a relatively low pressure. To this end I provide for reciprocating pumps 27, each of which comprises a cylinder 28 and a piston 29. The pistons are actuated by rods that are connected to extensions 30 of the two outside cross-heads 17. These pumps are arranged 110

to deliver air to the chambers 31 which are in communication with the chambers 32 that surround the scavenging ports 13. In order to simplify the illustration I have omitted the valve mechanism of these pumps, but it is to be understood that they will be provided with such mechanism of any suitable construction. I have referred to these pumps as being utilized to supply air for scavenging purposes, but one or more of said pumps may be employed to supply high pressure air to the injectors 14 for injecting fuel into the combustion space between the pistons, subject to the control of any suitable form of valve mechanism. These pumps in addition to serving as such also assist in balancing the weights of the various parts of the engine.

Referring to Fig. 4 I have shown a bridge piece or member 33 which is arranged to connect the outside crossheads 18 so as to prevent side thrusts on the cross-heads, due to the diagonal relation of the connecting rods, from being transmitted to the guide 26. I may use these bridge members on the inner as well as the outer cross-heads, all said members being so shaped as not to interfere with the movements of the cross-heads and rods attached to the pistons of the central cylinder.

It is important to arrange the diagonally extending connecting rods both in the front and in the rear of the cylinders because in this manner the stresses on the parts will be uniformly distributed thus avoiding objectionable thrust on the cylinder walls, cross-heads and associated parts.

I have shown my invention as applied to a vertical cylinder engine, but it is to be understood that the cylinders may be disposed horizontally or in any other desired position. I regard the vertical arrangement, however, as being the preferred one.

I am aware that both steam and internal combustion engines have heretofore been proposed having two cylinders arranged side by side, each cylinder having oppositely moving pistons, the inner piston in each cylinder being connected to the outer piston in the other cylinder by diagonally-extending connecting-rods. In such an engine when one pair of pistons is forced apart by the motive fluid admitted to the cylinder space between them on the working stroke, a stress of considerable magnitude is transmitted to the main shaft bearing. This stress alternates first on one bearing and then on the other. In my improved engine this bearing stress is avoided on the working stroke because as the pistons in the central cylinder move apart those in the outer cylinders approach each other and hence the stresses are transmitted not to the bearings but to the main shaft. When the pistons in the two outside cylinders move apart

on the working stroke, those in the central cylinder approach each other and again the stresses are transmitted through the main shaft and not to the bearings. To state the matter briefly in another way, the main shaft bearings are, by reason of the construction described, unloaded on each working stroke instead of being loaded as heretofore. In any two cylinder arrangement having oppositely moving pistons with diagonal or equivalent connecting-rods between pistons of adjacent cylinders first one main bearing and then the other will be loaded.

In the engine described herein there is a greater turning moment on the shaft due to the pistons of the outside cylinders than to those of the central cylinders, but for certain classes of work, notably for heavy traction motor cars, this is not only unobjectionable but may in some cases be advantageous as it tends to prevent periodic engine vibrations from being transmitted to the vehicle body. In those cases where it is objectionable it can be avoided or largely reduced by making the diameter of the central cylinder greater than that of either of the outside cylinders.

My improved engine also has the very great advantage of being very short for the output, a feature that will be appreciated when it is considered that the saving of each foot in shaft length has a monetary value of approximately \$800, in installations for which my engine is intended.

The decrease in length of the engine is due to the fact that only three cranks are used for six pistons and that they are connected to the cranks by the usual connecting rods and by diagonal connecting rods arranged in the manner aforesaid. This also permits the cylinders to be placed side by side in close proximity because space does not have to be provided between them for the rods connecting the outer pistons and the cranks.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. In an engine, the combination of three cylinders arranged side by side, a pair of oppositely moving pistons for each cylinder, a main crank shaft, connecting-rods connecting the three inner pistons with the shaft, means connecting the inner piston of the central cylinder with the two outer pistons of the outside cylinders, means connecting

the outer piston in the central cylinder with the two inner pistons in the outside cylinders, and means admitting motive fluid to the cylinders and exhausting it therefrom.

5 2. In an internal combustion engine, the combination of three cylinders arranged side by side, each cylinder having scavenging and exhaust ports, a pair of oppositely moving pistons located in each cylinder arranged to control said ports, means admitting motive fluid to each cylinder between the pistons, a main shaft having three cranks, a connecting rod between each of the inner pistons and a crank, a pair of diagonally-arranged rods which connect the inner piston of the central cylinder with the two outer pistons in the outside cylinders, and a pair of diagonally-arranged rods which connect the outer piston of the central cylinder with the two inner pistons of the outside cylinders.

20 3. In an engine, the combination of three open-ended cylinders arranged side by side, each being provided with ports near its outer ends, means admitting motive fluid to each cylinder at its central part, a pair of oppositely moving pistons located in each cylinder and arranged to control its ports, cross-heads for said pistons, diagonal rods arranged in pairs in the front and in the rear of the cylinders which connect the cross-head of the central inner piston with the cross-heads of the two outer pistons of the outside cylinders, and other diagonal rods also arranged in pairs in the front and in the rear of the cylinders which connect the cross-head of the central outer piston with the cross-heads of the inner pistons of the two outside cylinders.

40 4. In an engine, the combination of three cylinders arranged side by side, a pair of oppositely moving pistons for each cylinder, a main crank shaft, connecting rods connecting the three inner pistons with the shaft, means connecting the inner piston of the central cylinder with the two outer pistons of the outside cylinders, means connecting the outer piston in the central cylinder with the two inner pistons in the outside cylinders, a member connected to pistons of

the outside cylinders to relieve side thrust, and means for admitting motive fluid to the cylinders and exhausting it therefrom.

5 5. In an internal combustion engine, the combination of three cylinders arranged side by side, each cylinder having exhaust and scavenging ports controlled by the pistons, fuel injectors for the cylinders, a pair of oppositely-moving pistons in each cylinder, a main shaft having three cranks, rods connecting the inner pistons with the cranks, cross-heads for the pistons, diagonally-extending rods arranged on opposite sides of the cylinders which connect the inner cross-head of the central cylinder with the outer cross-heads of the outside cylinders, other diagonally-extending rods also arranged on opposite sides of the cylinders which connect the outer cross-head of the central cylinder with the inner cross-heads of the outside cylinders, pumps for compressing air which is delivered to the cylinders, and extensions carried by the inner cross-heads for actuating said pumps.

25 6. In an internal combustion engine, the combination of three cylinders arranged side by side, each cylinder having exhaust ports, means for introducing fuel into the cylinders, a main shaft having three cranks, oppositely moving pistons in each cylinder, bearings therefor, cross-heads for each of the pistons, connecting rods uniting the inner cross-heads with the cranks, pairs of rods arranged in front and in back of the cylinders, each pair being connected to the same inner central cross-head at one end and to the outside upper cross-heads at the other, pairs of rods also arranged in front and in back of the cylinders, each pair being connected to the same outer central cross-heads at one end and to the outside lower cross-heads at the other, and guides for the cross-heads.

In witness whereof, I have hereunto set my hand this seventeenth day of April, 1913.

GUSTAV H. KAEMMERLING.
